JACOB B. WALLACE, OF ERIE, PENNSYLVANIA; FLORENCE E. WALLACE, ADMINISTRATRIX OF SAID JACOB B. WALLACE, DECEASED, ASSIGNOR, BY MESNE ASSIGNMENTS, TO MODERN TOOL COMPANY, OF SAME PLACE.

DIE.

SPECIFICATION forming part of Letters Patent No. 680,448, dated August 13, 1901.

Application filed May 15, 1900. Serial No. 16,820. (No model.)

To all whom it may concern:

Be it known that I, JACOB B. WALLACE, a citizen of the United States, residing at Erie, in the county of Erie and State of Pennsylvania, have invented certain new and useful Improvements in Dies; and I do hereby declare the following to be a full, clear, and exact description of the invention, such as will enable others skilled in the art to which it applies to make and use the same.

This invention relates to dies; and it consists in certain improvements in the construction thereof, as will be hereinafter fully described, and pointed out in the claims.

More particularly, the invention relates to that class of dies which are adjustable and self-opening.

The invention is illustrated in the accompanying drawings, as follows:

Figure 1 shows a front elevation of the die. Fig. 2 shows a section on the lines 2 2 3 3 in Fig. 1.

A marks the shank on which the device is mounted. This shank is preferably mounted in the turret of a screw-machine. In the face of the shank A there is a bearing A', in which is journaled the head B. On the face of the head are arranged a series of guideways B', in which are the grooves b'. The chasers C are mounted on the blocks F. These blocks are provided with the tongues f, which fit in the grooves. The chasers are moved to and from the work by movement of the blocks in the guideways B'. The cam-ring D is mounted on the outer or bearing surface A² of the shank A. The front part of the cam-ring is provided with the cam-surfaces d, which are arranged to operate upon the cam-surfaces f' of the blocks F. Each of the blocks is provided with a radial opening f, closed at the outer ends by the screw-plug f³. Opening into this radial opening is the slot f⁴. A screw f⁶ extends from the head B through the slot f⁴ into the radial opening f². A spring f⁵ is tensioned against the head of the screw f⁶ and the screw-plug f³. This spring presses the block against the cam-surface d, so that when the cam-ring is moved around to bring the cam-surface d out of register with the cam-

surface f' the blocks F are moved outwardly, so as to move the chasers C out of operative position.

Arranged on the face of the head B is a circumferential groove b'. A screw d' extends from the cam-ring D into this groove and locks the cam-ring against axial movement on the head. A screw b² is secured to the head in the groove b'. A spring d² extends from the screw d' to the screw b² and tends to rotate the cam-ring D to throw the cam-surfaces d out of register with the cam-surfaces f', so as to allow the springs f⁵ to open the die.

Arranged in a slot d³ in the under side of the cam-ring is an adjusting-block D. Extending from this adjusting-block D' is a set-screw d⁵. This set-screw extends through a slot d⁶ in the cam-ring. By loosening the set-screw the block D' may be moved circumferentially on the cam-ring. Arranged in this block is a groove d⁴, which extends in an axial direction along the face A² of the shank. Arranged on the shank is a lug a. This lug is of a size which will permit of its entry into the groove d⁴. A handle D³ is provided for rotating the cam-ring. An opening b³ extends into the face of the head B and is extended by a smaller opening b⁴ through the head. A screw G extends through the openings b³ and b⁴ and is screwed into the shank. The head g of this screw forms a sliding fit in the opening b³. A spring H is arranged in the opening b³ back of the head g. This spring tends to hold the flange of the head in contact with the shank A.

The operation of the device is as follows: The cam-ring is rotative until a lug a is brought into register with the groove d⁴. The tension of the spring H then snaps the head back into contact with the shank A, carrying the lug a into the groove d⁴, thus locking the cam-ring in the set position. The cam-ring in its set position brings the cam-surfaces d into register with the cam-surfaces f', so as to press the blocks F to the inner position desired. The die is then fed onto the work until the turret arrives at its provided stop, (not shown,) which determines the length of the screw. The work continu-

ing to turn operates upon the threads of the chasers, which, operating as a screw, carry the head B and the cam-ring D forward until the groove d^4 is carried past the lug a . 5 This relieves the cam-ring, and the spring d^2 immediately snaps the cam-ring to the open position and the spring f^5 snaps the blocks to their open position. This allows the turret to be moved back, carrying the dies away 10 from the work. In the ordinary operation of these devices a lug D^2 is provided, which contacts that part of the machine, so as to turn the cam-ring to its set position with a movement of the turret. With this construction 15 the cam-surfaces are exactly in line of the strain on the chasers, so that any bell-crank action is avoided. By this arrangement there is no springing of the device, and consequently when the device is once ad- 20 justed it continues to cut threads of exactly the same size, so that they may be used interchangeably whatever difference there may be in the quality of the material operated upon. This is a very important feature where 25 dies are used for making interchangeable work or where a continuous standard gage is desired.

It will be noted that the cam-surfaces up to the moment of release of the chasers cover 30 the entire surfaces of the chasers subjected to strain, so that there is no tendency to bell-crank action, and consequently an even thread is produced. This is accomplished in the present device by giving to the cam-sur- 35 faces a rotative movement, with the axis of the head as a center. In this way the cam-surfaces are moved over the chasers throughout their width at the same time. It will be noted also that the chasers are held to their 40 work until the head has reached a predetermined point, when they are immediately opened by the spring d^2 , so that the thread produced is of exactly the same depth throughout its length. From this it will be 45 seen that by preventing bell-crank action and holding the chasers to their work until released a thread of the same size throughout its length can be produced, if desired.

What I claim as new is—

50 1. In a die, the combination of a carrier; a head mounted on said carrier; chasers carried by said head; cams for moving said chasers to their work, and for locking said chasers in their set position, said cam-sur- 55 faces being arranged in the line of strain on said chasers; means for automatically moving said cam-surfaces to release said chasers from their set positions at a predetermined point; said means being arranged to operate 60 after being brought into action independently of the movement of the head; and springs operating independently of the cams arranged to open said chasers when released by the cam.

65 2. In a die, the combination with a carrier A; the head B slidingly mounted thereon and

having guides therein; chasers carried by said guides; the cam-ring D arranged to have rotative movement on the head and having the cam-surfaces d arranged in line with the strain 70 on the chasers; a spring mechanism operating independently of the cams for opening said chasers when released by the cam; means for locking the cam in the set position; and means for releasing the said locking mech- 75 anism when the head D is moved away from the shank or carrier A.

3. In a die, the combination with the carrier, A; the head, B, slidingly mounted thereon and having the guides for the chaser-block; 80 the blocks, F, mounted in said guides; chasers arranged in said blocks; the cam-ring, D, ar- ranged to have rotative movement with the axis of the head as a center, having the cam-surfaces, d , arranged in line with the strain 85 on the chasers; a spring mechanism for opening said blocks when released by the cam; said spring mechanism being independent of the cam; means for locking the cam in a set position; and means for releasing said lock- 90 ing mechanism when the head, B, is moved away from the shank or carrier, A.

4. In a die, the combination of the shank, A; the head, B; mounted thereon, having the openings, b^3 and b^4 therethrough; circum- 95 ferential grooves, b , therein; and the guides, B', therein; the blocks, F, arranged in the guides, B', said blocks being provided with the opening, f^2 , and slot, f^3 ; the spring, H, arranged in the opening, b^3 ; the spring, f^5 , 100 being arranged in the opening, f^2 ; the cam-ring, D, having the cam-surfaces, d , therein; a spring d^2 , arranged in the circumferential slot, b , and tensioned between the cam-ring and the head to rotate the cam-ring in a di- 105 rection to open the die; a groove-and-lug mechanism arranged between the cam-ring and the shank and arranged to be brought out of engagement by an axial movement of the head on the shank. 110

5. In a die, the combination of the shank, A; the head, B, mounted thereon, having the openings, b^3 and b^4 , therethrough; circum- 115 ferential grooves, b , therein; the guides, B', therein; the block, F, arranged in the guides, B', said blocks being provided with the open- 120 ings, f^2 , and slot, f^3 ; the spring, H, arranged in the opening, b^3 ; the spring, f^5 , arranged in the opening, f^2 ; the cam-ring, D, having the cam-surfaces, d , thereon; a spring, d^2 , ar- 125 ranged in the circumferential slot, b , and tensioned between the cam-ring and the head to rotate the cam-ring in a direction to open the die; a groove-block arranged on said cam; means for adjusting said block; a lug on the shank adapted to register and enter said groove when the cam is moved to a set position, and to be thrown out of said groove by an axial movement of the head relatively to the shank. 130

6. In a die, the combination of a carrier; a head mounted on said carrier; chasers car-

ried by the head; the cam-ring, D, having the slot, d^6 , and a groove, d^3 , therein; the adjusting-block, D', arranged in the groove, d^3 ; the set-screw, D⁵, passing through the groove, 5 D⁶, into the block, D', and having the groove d^4 , therein; the lug, a, fixed on the carrier and arranged to enter the groove, d^4 , when brought into register therewith; and means

for moving said cam-ring away from said lug, a, and by said lug, a, to disengage the chaser. 10
In testimony whereof I affix my signature in presence of two witnesses.
